UNITED STATES PATENT OFFICE.

SAMUEL TRUAN HOAR, OF MEADERVILLE, MONTANA.

BLASTING APPARATUS.

1,369,658.

Specification of Letters Patent. Patented Feb. 22, 1921.

Application filed June 18, 1919. Serial No. 305,043.

To all whom it may concern:

Be it known that I, SAMUEL T. HOAR, a citizen of the United States, residing at Meaderville, in the county of Silver Bow 5 and State of Montana, have invented new and useful Improvements in Blasting Apparatus, of which the following is a specification.

My invention relates to electrical apparatus for use in blasting, or the like, and has particular reference to a switch adapted for closing a number of circuits for exploding electric primers, and to improvements in the construction of such primers.

15 An important object of the invention is to provide an electric switch of the above mentioned character, by the employment of which a number of charges may be fired in proper order, and the charges which fail 20 to explode indicated.

A further object of the invention is to provide a switch of the above mentioned character, which is simple in construction and reliable and convenient in use.

25 A further object of the invention is to provide an explosive charge which may be completely assembled before being distributed to the miner, so that all the miner need do is to place the same in the hole to 30 be blasted and connect it in the circuit.

A further object of the invention is to provide an explosive charge device or primer, which may be used in a damp or wet hole without liability of failure in operation.

Other objects and advantages of the invention will be apparent during the course of the following description.

In the accompanying drawings, forming 40 a part of this specification, and in which like numerals are employed to designate like parts throughout the same,

Figure 1 is a side elevation of a switch embodying my invention,

45 Fig. 2 is a similar view of the switch, showing it connected with the circuits,

Fig. 3 is a longitudinal sectional view taken on line 3—3 of Fig. 1,

Fig. 4 is a horizontal transverse sectional view taken on line 4—4 of Fig. 1,

Fig. 5 is a longitudinal sectional view through the exploding device or charge, showing the primer therein,

55 Fig. 6 is a detail section through the upper end of the primer,

Fig. 7 is a longitudinal section through a different form of exploding device or charge.

In the drawings, wherein for the purpose of illustration is shown a preferred embodiment of my invention, the numeral 10 designates a support or cross head, which is preferably formed of insulating material. The support 10 is provided with pairs of binding posts 11, and these pairs are vertically spaced. The horizontal pairs of binding posts 11 are connected with spaced transverse contacts 12, which are stationary and are preferably held close to the support 10.

A transverse bar 13 is rigidly secured to the lower end of the support 10 and is preferably formed of insulating material. The bar 13 has transverse openings for the reception of connecting wires 15, which are secured to the binding posts 11. A signal device, such as a lamp or buzzer 15' is connected in wire 15. There may be any suitable number of these connecting wires, the same being preferably numbered by reference characters 16, applied upon the transverse bar 13. The reference characters 16 also indicate the number of the holes to be blasted, and to which the wires lead. The wires 15 have their lower ends projecting downwardly beyond the bar 13 so that other wires may be tied or connected therewith, as may be desired.

A guide is carried by the support 10, comprising longitudinal members or bars 18 preferably formed of insulating material and spaced for forming a longitudinal passage 19. The outer side of the passage 19 is covered by a strip 20 which may also be of insulating material. The stationary contacts 12 extend behind the bars 18 and are adapted to be successively engaged by a movable contact 21, carried upon the lower end of a slide 22, operating within the passage 19. The slide 22 may be formed of insulating material and a main lead wire 23 extends longitudinally thereof, upon its outer side and is connected with the contact 21. This contact 21 may be a continuation or end of the wire 23, such wire being passed through transverse openings 24. The upper end of the wire 23 passes through a transverse opening 25, in the top of the slide 22. As shown in Fig. 3, when the slide is in the lowermost position the contact 21 is arranged beneath the lowermost contact 12,

but as the slide 22 is raised the contact 21 successively engages the contacts 12.

In Fig. 2 the numeral 26 designates the other main lead wire, the wires 23 and 26 being connected with the opposite poles of a source of current, not shown. The lower end of the wire 26 embodies sections 27 and 28, as shown. Wires 29 are connected with the lower ends of the wires 15, any suitable number of the wires 29 being employed. The wires 29 are connected with the wire sections 27 or 28, as shown. These wires 29 have electrically actuated exploding devices or charges 30, connected in series therewith. These exploding devices will be described later.

The operation of the apparatus thus far described is as follows:

When the slide 22 is elevated to the first position the contact 21 will engage the lowermost contact 12, and circuits will be closed whereby the devices 30 arranged within the holes No. 1 will be exploded, these holes being indicated by the numerals 16. In these closed circuits, current flows through the wire 26; section 27 thereof, exploding device 30, wire 29, wire 15 in hole No. 1, lowermost contact 12, and through wire 23 back to the opposite pole of the source of current. The current also flows through the section 28 of the wire, the wire 29 in the other hole No. 1, wire 15, contact 12, contact 21, and through wire 23 back to the opposite pole of the source of current. It is obvious that as the slide is elevated, the contact 21 is successively brought into engagement with the contacts 12, and closing one or two circuits, as the case may be, depending upon whether or not one or two wires 29 are connected with the two wires 15.

The exploding device 30 may be of the form shown in Fig. 5, wherein the exploding charge 31 may be dynamite, the same being held within a casing 32. This dynamite is provided with a longitudinal opening or bore 33, to receive a primer to be next described. This primer embodies an inner casing 34, having a longitudinal opening 35, for the reception of a powder train 36 or fuse. The numeral 37 designates a metallic element of high resistance, which is adapted to glow upon the passage of current therethrough. The metallic element 37 extends across the powder train or fuse 36 and is 55 adapted to ignite the same when the metallic element blows. Wires 38 engage the ends of the element 37 and these wires are preferably bound to the casing 34 by a wrapping 39. The wires 38 are suitably connected 60 with the wires 29 and 26, as is obvious. The lower end of the casing 34 is suitably connected with a blasting cap 40, which is exploded by the ignition of the powder train 36, leading thereto.

To protect the fuse and cap 40 from the

action of the water or moisture the same is arranged within a tube 41, which may be formed of rubber, paper or like material. The ends of this tube project outwardly beyond the fuse casing and cap and such ends are closed by water proofing material 42, which may be soap or grease. However, the tube 41 may be omitted, if desired.

The upper end of the outer casing 32 may be closed by a stopper 43, also serving to clamp the wires 38 to the casing 32, there being suitable slack in the portions of the wires 38 within the casing 32.

In Fig. 7 the numeral 44 designates an explosive charge, such as dynamite, held within a casing 45, the upper end of which projects above the same. The casing 45 receives the lower end of an upper casing 46, containing a fuse 47 of suitable length. The upper end of this fuse contains a heat resistance element similar to the element 37, to ignite the powder train of the fuse 47. This heat resistance element is connected with wires 48, corresponding to the wires 38. The lower end of the fuse 47 is connected with a blasting cap 49, serving to explode the charge 44, when it explodes. A stopper 50 closes the upper end of the casing 46, as shown.

It is obvious that either form of explosion device may be employed in connection with my improved switch, such device being exploded when the circuit is closed, as hereinabove described.

It is to be understood that the forms of my invention herewith shown and described are to be taken as preferred examples of the same, and the various changes in the shape, size, and arrangement of parts, may be resorted to without departing from the spirit of my invention or the scope of the subjoined claims.

Having thus described my invention, I claim:

1. In a switch of the character described, a support, spaced contacts carried by the support, a pair of guide bars arranged upon the support and secured thereto, a cover strip secured to the guide bars, a slide arranged between the guide bars and having a pair of spaced apertures and a wire extending longitudinally of the slide and having its end portion passed through the apertures for forming a contact element, said contact element being adapted to successively engage said spaced contacts.

2. In a switch of the character described, a support, spaced contacts carried by the support, a slide of insulating material associated with the support and adapted to traverse the said contacts, said slide having a pair of spaced apertures, and a wire extending longitudinally of the slide and having a portion passed through the apertures for forming a contact element, said contact element being

adapted to successively engage the spaced contacts as the slide traverses said contacts, all as and for the purposes specified.

3. In a switch of the character described, a support, spaced contacts carried by the support, a slide of insulating material associated with the support and adapted to traverse the said contacts, and a conductor extending longitudinally of the slide and insulated thereby for a portion of its length and having an exposed portion constituting a contact element, said contact element being adapted to successively engage said spaced contacts as the slide traverses the same, all as and for the purposes specified.

4. In a switch of the character described, a support, transverse pairs of binding posts carried by the support and arranged in spaced relation upon the upper side thereof,

transverse contacts connected with the binding posts, an apertured transverse bar secured to one end of the support, wires passing through the apertures of the bar and secured to the binding posts, a pair of guide bars arranged upon the upper surface of the support and secured thereto and engaging the transverse contacts and secured to the support, said guide bars being spaced, a cover strip secured to the guide bars, a slide arranged between the guide bars and having a pair of spaced apertures, a wire extending longitudinally of the slide and having its end portion passed through the apertures for forming a contact element, said contact element being adapted to successively engage the transverse contacts.

SAMUEL TRUAN HOAR.
